UNITED STATES PATENT OFFICE.

WILLIAM H. SPENCER, OF BROOKLYN, NEW YORK, ASSIGNOR TO GEORGE FRINK SPENCER, OF NEWARK, NEW JERSEY.

COMBINED REFLECTOR AND SOCKET HOOD.

No. 816,756.

Specification of Letters Patent.

Patented April 3, 1906.

Application filed May 2, 1905. Serial No. 258,462.

To all whom it may concern:

Be it known that I, WILLIAM H. SPENCER, a citizen of the United States, residing at Brooklyn, in the county of Kings and State 5 of New York, have invented certain new and useful Improvements in a Combined Reflector and Socket Hood; and I do hereby declare the following to be a full, clear, and exact description of the invention, such as will 10 enable others skilled in the art to which it app pertains to make and use the same, reference being had to the accompanying drawings, and to figures of reference marked thereon, which form a part of this specification.

15 This invention has reference generally to improvements in reflectors of that class which are provided with a hood or receptacle for the reception of an incandescent or other lamp-receiving socket, and the invention has 20 reference more particularly to a novel construction of combined reflector and socket hood of the general character hereinafter more fully specified.

25 My invention has for its principal objects to provide a novel arrangement and construction of combined reflector and socket hood which is connected therewith in such a manner that there shall be no exposed joints at the connection of the said hood with the 30 reflector, all with a view of providing a cheap and simply-made reflector and socket hood, which shall be waterproof from the top of the device.

35 Another object is simplicity of construction in the manner of arranging the socket-hood in a central opening of the reflector-shell and simple manner of securing the lower marginal edge portion of the hood to an inner and downwardly-projecting rim of 40 the said reflector, the connected parts being fully covered at their joints with the enamel usually employed, and whereby a strong and fully waterproof connection is produced, thereby fully overcoming the rusting away 45 of the parts at their joints of connection.

Other objects of this invention not at this time more particularly mentioned will be clearly evident from the following detailed description.

50 With the various objects of my invention in view the said invention consists in the combined reflector and socket hood hereinafter set forth; and, furthermore, this invention consists in the various arrangements and

combinations of parts, all of which will be 55 hereinafter more fully described and then finally embodied in the clauses of the claim which are appended to and form an essential part of this specification.

The invention is clearly illustrated in the 60 accompanying drawings, in which—

Figure 1 is a side view of the combined reflector and socket hood embodying the principles of the present invention. Fig. 2 is a top or plan view of the same, and Fig. 3 is a 65 bottom view of the combined reflector and socket hood. Fig. 4 is a central longitudinal vertical section of the combined reflector and socket hood, with an incandescent-lamp receiving socket shown in position in the hood, 70 said socket being represented partly in elevation and partly in section, and said view showing one manner of retaining means for connecting the lower marginal edge portion of the socket-hood with the inner and annular rib or flange of the reflector shell or body. Fig. 5 is a collective perspective view of the 75 socket-hood and the central portion of the said reflector shell or body, clearly showing the inner annular rib or flange of the said 80 shell or body and the manner of assembling said parts. Fig. 6 is a detail sectional representation, on an enlarged scale, of portions of the reflector shell or body, the socket-hood, and the socket, illustrating more 85 clearly the preferred manner of connecting these parts. Fig. 7 is a central longitudinal vertical section of a combined reflector and socket hood, showing a modified form of fastening means for operatively connecting the 90 reflector-hood with the inner annular flange or rib of the reflector shell or body.

Similar characters of reference are employed in all of the said above-described views to indicate corresponding parts.

In the said drawings the reference character 1 indicates the complete reflector and socket hood; 2, the reflector shell or body; 3, the socket-hood, and 4 the usual lamp-socket, made of porcelain or other similar material 100 and adapted to receive in the usual and well-known manner the screw-threaded end portion of an incandescent lamp. The said reflector shell or body 2 is usually made from sheet metal and is made concavo-convex, as 105 shown in the several figures of the drawings, the same being preferably bounded upon its marginal edge by a suitable bead 5. The

said reflector shell or body 2 is also made with a centrally-disposed opening 6, which is surrounded upon the inner surface of the said shell or body 2 by an inwardly and down- 5 wardly extending annular flange or rib 7, as clearly illustrated. The said annular flange or rib 7 is provided with any suitable number of receiving holes or perforations 8. The said socket-hood 3 is also preferably made 10 from sheet metal, the same being of the general bell-shape configuration shown in the accompanying drawings. In its upper open portion the said hood 3 is provided with a suitably-secured fitting or screw-ring 9 for 15 securing the combined reflector and socket hood to a fixture, (not shown here,) the said fitting or screw-ring being preferably provided with a suitable holding or binding set- screw 10. The said socket-hood 3 may also 20 be provided at its lower marginal edge with a head or turnover 11, substantially as shown in Figs. 4, 5, and 6, and with a number of holes or perforations 12, which correspond in 25 number and position to the number and positions of the holes or perforations 8 in the annular flange or rib 8 of the reflector shell or body 2. The holes or perforations 12 in the socket-hood, as will be seen, are preferably surrounded upon the outer face of the hood 30 with slightly-raised marginal projections or flanges 13, the purposes of which will presently appear. Thus when the smaller and upper end portion of the said socket-hood 3 is inserted and passed through the central open- 35 ing 6 from the inner surface of the reflector shell or body 2 until the annular bead or turnover 11 is brought against the marginal edge of the annular flange or rib 7 of the reflector shell or body 2 the marginal projec- 40 tions or flanges 13, which surround the holes or perforations 12 in the bell-shaped socket-hood 2, are easily forced or sprung into holding engagement with the receiving holes or perforations 8 in the flange or rib 7 of the reflector shell or body, as will be clearly evi- 45 dent and as shown more particularly in Fig. 6 of the drawings. In this manner the reflector shell or body 2 and the socket-hood 3 are easily and quickly brought into their as- 50 sembled relation, and the connected parts are now ready for the enameling process. The outer surfaces of the socket-hood 3 and the reflector shell or body 2 are then provided with a covering of enamel of any suitable 55 color, usually green, this enamel covering extending around the marginal edge and slightly upon the under and inner face of the said reflector shell or body 2, as at 15. The under and inner face of the reflector shell or 60 body 2 is provided with a white enamel coating 16, which extends from the enameled portion 15 to the outer surface of the annular flange or rib 7 of the said reflector shell or body 2, all of which is clearly illustrated in 65 Figs. 4, 6, and 7 of the drawings. In this

manner, while I have simplified the construction and method of securing the socket-hood in its position upon the reflector shell or body 2 without the use of solder or other expensive fastening devices, it will be clearly seen that 70 the reflector is perfectly waterproof from the top and at the point of connection of the said socket-hood with the reflector shell or body.

In Fig. 7 of the drawings I have shown a slightly-modified means for securing the lower marginal portion of the said socket-hood 3 to the annular flange or rib 7 of the said reflector shell or body 2. In this instance the said socket-hood is made at its lower end with a bead 17, which is closed 80 around the lower edge of the said flange or rib 7 and serves to operatively connect and secure the two parts together.

The porcelain or other suitable lamp-socket 4 is detachably and removably se- 85 cured within the said hood 3 by means of suitable screws 18, which are passed through the respective holes or perforations 8 and 12 in the flange or rib 7 and the hood, the screw-threaded portions of said screws being 90 screwed into receiving nuts or plates 19, placed in suitable nut-receiving sockets or depressions 20, formed in the said lamp-socket 4, substantially as shown in Figs. 4, 6, and 7. It will be understood, however, that 95 these screws 18 may be otherwise secured to the said socket 3, if desired.

From the foregoing description of my present invention it will be seen that I have devised, in addition to the various objects 100 and benefits hereinabove stated, a combined reflector and socket hood in which the lamp-socket 4 is removably disposed, so as to enable the removal of the lamp-socket from the socket-hood for necessary repairs without 105 disturbing the position of the socket-hood 3, as is the case in the constructions as now ordi- narily made. This fixed arrangement of the socket-hood with the reflector shell or 110 body enables me to entirely cover over the joint between these parts with the enamel, thus providing a continuous covering of en- 115 amel and in consequence producing a com- bined reflector and socket hood which is per- fectly waterproof from the top.

I claim—

1. A combined reflector and socket hood, comprising a reflector-shell having a centrally-disposed opening, an inner and down- 120 wardly-extending rib surrounding the said opening, said rib being provided with receiving-holes, a socket-hood in said opening, said hood being provided with receiving holes registering with the holes in said rib, means arranged in and extending through said reg- 125 istering holes for securing said hood in a fixed position in said opening and a continu- 130 ous and unbroken enamel or other layer upon the outer surfaces of said hood and reflector- shell, said layer entirely closing the joint be-

tween said hood and reflector-shell to provide a reflector which is waterproof at the top, substantially as and for the purposes set forth.

5 2. A combined reflector and socket hood, comprising a reflector - shell having a centrally-disposed opening, an inner and downwardly - extending rib surrounding the said opening, a socket-hood in the said opening, 10 means connected with the said rib for securing said hood in a fixed position in said opening, and a continuous and unbroken enamel or other layer upon said outer surfaces of said hood and reflector-shell, said layer entirely 15 closing the joint between said hood and reflector-shell to provide a reflector which is waterproof at the top, substantially as and for the purposes set forth.

3. A combined reflector and socket hood, 20 comprising a reflector - shell having a centrally-disposed opening, an inner and downwardly - extending rib surrounding the said opening, said rib being provided with receiving holes, a socket-hood in said opening, said 25 hood being provided with holes or perforations near its lower edge portion, said holes or perforations in the hood being surrounded with outwardly - extending projections, said 30 projections extending into and being in holding engagement with the holes in said rib for securing said hood in a fixed position in the opening of the reflector-shell, and a continuous and unbroken enamel or other layer upon 35 said outer surfaces of said hood and reflector-shell, said layer entirely closing the joint between said hood and reflector-shell to provide a reflector which is waterproof at the top, substantially as and for the purposes set forth.

40 4. A combined reflector and socket hood, comprising a reflector - shell having a centrally-disposed opening, an inner and downwardly - extending rib surrounding the said opening, said rib being provided with receiving holes, a socket-hood in said opening, said 45 hood being provided with holes or perforations near its lower edge portion, said holes or perforations in the hood being surrounded with outwardly - extending projections, said 50 projections extending into and being in holding engagement with the holes in said rib for securing said hood in a fixed position in the opening of the reflector - shell, a bead upon the lower marginal edge portion of said 55 socket-hood, said bead abutting against the lower edge of said rib, and a continuous and unbroken enamel or other layer upon said outer surfaces of said hood and reflector-shell, said layer entirely closing the joint between 60 said hood and reflector - shell to provide a reflector which is waterproof at the top, substantially as and for the purposes set forth.

5 A combined reflector and socket hood,

comprising a reflector - shell having a centrally-disposed opening, an inner and downwardly - extending rib surrounding the said opening, said rib being provided with receiving holes, a socket-hood in said opening, said 65 hood being provided with holes or perforations near its lower edge portion, said holes or perforations in the hood being surrounded with outwardly - extending projections, said 70 projections extending into and being in holding engagement with the holes in said rib for securing said hood in a fixed position in the opening of the reflector-shell, a continuous and unbroken enamel or other layer upon 75 said outer surfaces of said hood and reflector-shell, said layer entirely closing the joint between 80 said hood and reflector-shell to provide a reflector which is waterproof at the top, a lamp-receiving socket removably arranged in said hood, said lamp - receiving socket having nut-receiving depressions, nuts 85 in said depressions, and screws extending through the registering perforations in said rib and the socket-hood, said screws being screwed into said nuts, substantially as and for the purposes set forth. 90

6. A combined reflector and socket hood, comprising a reflector - shell having a centrally-disposed opening, an inner and downwardly - extending rib surrounding the said opening, said rib being provided with receiving holes, a socket-hood in said opening, said 95 hood being provided with holes or perforations near its lower edge portion, said holes or perforations in the hood being surrounded with outwardly - extending projections, said 100 projections extending into and being in holding engagement with the holes in said rib for securing said hood in a fixed position in the opening of the reflector-shell, a bead upon the lower marginal edge portion of said 105 socket-hood, said bead abutting against the lower edge of said rib, a continuous and unbroken enamel or other layer upon said outer surfaces of said hood and reflector-shell, said 110 layer entirely closing the joint between said hood and reflector-shell to provide a reflector which is waterproof at the top, a lamp-receiving socket removably arranged in said hood, said lamp-receiving socket having nut-receiving depressions, nuts in said 115 depressions, and screws extending through the registering perforations in said rib and the socket-hood, said screws being screwed into said nuts, substantially as and for the purposes set forth. 120

In testimony that I claim the invention set forth above I have hereunto set my hand this 26th day of April, 1905.

WILLIAM H. SPENCER.
